Des. 228,587
Patented Oct. 16, 1973

228,587

HIGH CHAIR WITH REMOVABLE SEAT

Lawrence Blazey, Bay Village, David Silverstrom, Lyndhurst, and Elmer Rocker, Shaker Heights, Ohio, assignors to Century Products, Inc., Cleveland, Ohio

Filed Feb. 7, 1972, Ser. No. 224,402

Term of patent 14 years

Int. Cl. D6—01

U.S. Cl. D6—8

Fig. 2

Fig. 1

FIG. 1 is a front perspective view of a high chair with removable seat showing our new design;

FIG. 2 is a rear perspective view;

FIG. 3 is a perspective view taken from the right; and

FIG. 4 is a perspective view of the removable seat.

We claim:

The ornamental design for a high chair with removable seat, substantially as shown.
